UNITED STATES PATENT OFFICE.

JOSEPH H. MILLER, OF STEVENS POINT, WISCONSIN.

FESTOONING MACHINE FOR CARRYING PAPER AND THE LIKE.

Application filed July 16, 1924. Serial No. 726,373.

To all whom it may concern:

Be it known that I, JOSEPH H. MILLER, a citizen of the United States, residing at Stevens Point, in the county of Portage and 5 State of Wisconsin, have invented certain new and useful Improvements in Festooning Machines for Carrying Paper and the like; and I do hereby declare the following to be a full, clear, and exact description of 10 the invention, such as will enable others skilled in the art to which it appertains to make and use the same.

This invention relates to apparatus and method for handling wet paper in web or 15 continuous form while hung up in festoons in passing through the drying loft and has for its object to prevent so-called "stick marks" in the material being dried. These marks are caused by the paper resting or 20 being carried on the sticks in the same position during the time of drying and are in the nature of a permanent set in the paper.

In accordance with the present invention there is provided an apparatus which will 25 permit the different portions of the paper being alternately supported on the stick while the paper is being progressed through the drying loft thus permitting each portion to dry normally during the interval 30 when not in contact with the supporting stick and hence preventing the paper from acquiring permanent pole or stick marks. The apparatus is so constructed that the poles supporting the paper are each periodically 35 turned in unison in a given direction and periodically reversed. The reversal of the direction of rotation of the sticks at intervals keeps the paper suspended in substantially the same relative position with respect to the travelling carrier of which the 40 sticks or poles are a part.

In the ordinary festoon system of drying, the paper or other material is carried through the drying room or tunnel by being 45 hung from sticks or poles in loops or festoons of approximately equal length. For different classes and grades of material the length of loop or festoon is ordinarily some length between one foot and ten feet from 50 top to bottom. The poles or sticks carrying the paper or other material are caused to move through the drying room or tunnel, either by being carried on a travelling chain or chains, or by being pushed along a fixed 55 track by fingers attached to a reciprocating bar, which causes the fingers to push the

sticks forward a certain distance, moves back to its original position, then moves forward again, and so on. My improvement may be adapted to either of these systems of carrying the sticks.

The various features of novelty and invention will appear from the detailed description taken in connection with the accompanying two sheets of drawings forming part of this specification.

Referring to the drawings, Fig. 1 is a perspective view, in more or less diagrammatic form, showing the paper supported in festoons on the improved sticks.

Fig. 2 is an enlarged vertical sectional view through one side of the frame on which the sticks are supported.

Fig. 3 is a section taken on line 3—3 of Fig. 2.

Fig. 4 is a section taken on line 4—4 of Fig. 2.

Fig. 5 is an elevation of one end of the improved sticks.

Fig. 6 is a group of three diagrammatic views to illustrate the different positions of the sticks with respect to the paper; and

Fig. 7 is a perspective view of a modified form of the means for imparting turning movement to the sticks.

In Figs. 1 and 6, numeral 1 indicates the paper or other material to be dried. The paper is shown as hung in festoons on sticks or poles of special form, the poles being generally indicated by S. As shown, each 90 pole comprises a pair of round rods 2 and 3, maintained in relatively fixed relation by having both their adjacent ends secured to spacing blocks 4 in any suitable manner.

The ends of the poles S are provided with 95 shafts 5 on which are mounted turnable bearing blocks 6, the shafts being suitably anchored in the spacing blocks 4. It will be understood that the axes of the shafts 5 are in alinement and are midway between the 100 pole rods 2, 3.

The machine frame includes a plurality of yokes having arms 10 and 11 to which are secured T-iron rails 12 and 13. The webs of these rails are vertically disposed and on one side of the same are disposed guide rails 7 and 8 between which is slidably received the bearing block 6 of the pole S.

The paper is usually progressed through 110 the drying loft or tunnel in a step-by-step movement and to that end the poles are

pushed along periodically. A convenient form of pusher mechanism includes transversely extending bars 16 connected by rails 18 which ride on rollers 17 mounted on the yokes 9. The bars 16 carry pawls 20 pivoted on a support 19 which extends between the said bars. The pawls are so arranged as to slide over and drop behind the bearing blocks 6 as the pusher bar 16 is moved back and forth by any suitable mechanism not shown. It will be understood that the poles S will be moved forward in unison with the pusher bars 16 but will remain stationary on the return stroke of the pusher bars. In place of pusher bars chains which periodically progress may be employed.

Means are provided to cause the double-rod poles S to rotate first in one direction and then in the opposite direction to support the paper first on one rod and then on the other, as the poles are pushed along.

Referring to Fig. 6, the upper figure of the group shows the rod 2 as supporting the paper while the lower figure shows the paper supported on the rod 3. The intermediate figure shows how the paper is transferred from one rod to the other, the rotation of the pole as a whole being counterclockwise in these views. The transfer of the paper from one rod to another is effected during the period the pole is being pushed along. With respect to Fig. 6 the next translatory movement of the pole will cause the pole to turn in a clockwise direction whereby the rod 2 will again support the paper in approximately the same place as before, as will now be readily understood.

The novel means for imparting alternate turning movement to the double-rod pole will now be described. Non-turnably affixed to the pole, preferably at each end thereof, is a round wheel or disk 27, the same being eccentrically positioned with respect to the shaft 5. Mounted on the T-irons 12 and 13 are two series of upper and lower cam blocks 26 and 25 arranged in staggered relation. Through the zigzag path formed by these cam blocks the disk wheel 27 is designed to move, the action being such that the wheel is swung or turned one half revolution in passing through the gateway 28 formed by the adjacent ends of the cam blocks, as will be readily apparent by reference to Fig. 3. The diameter of the wheel or disk 27 is such that it will just pass through the space or gateway 28 constituted by the opposite adjacent ends of the cam blocks 25 and 26. In Figs. 2 and 3 the wheel is positioned over one of the lower cam blocks 25. Assuming that the sticks S are moving toward the right as viewed in Fig. 3, the wheel will maintain its position as shown in full lines in Fig. 3 until it engages the rounded end 29 of the upper cam block when it obviously must turn in

a counterclockwise direction in order to pass through the gateway between the adjacent ends of said cam blocks 24 and 26, and such turning will be approximately one-half revolution. In further explanation of the action, it may be stated that the wheel upon being forced against the rounded end 29 of the cam block is given more than a rolling motion as it contacts with the rounded end or cam surface 29 of the cam block; it is caused to swing or turn faster than would be the case if it merely rolled along the cam surface 29. The surface of the wheel and the rounded surface of the cam block 29 are therefore smooth in order to permit relative sliding action when the wheel engages with the said rounded surface. The rotary movement imparted to the sticks S by means of the wheel and cam blocks is sufficient to turn said sticks through one-half revolution, as has already been explained in connection with Fig. 6. If the pole S were being moved toward the left as viewed in Fig. 3, it is clear that the pole would be turned in a clockwise direction as the wheel passed beneath the upper cam block 26. It will be further appreciated that the arrangement is such that the pole is turned first in one direction and then in the opposite direction as the pole is pushed or moved along.

A modified form of means for obtaining rotation of the stick S is shown in Fig. 7. In place of the eccentric wheel there may be provided a pinion 30 and in place of the cam blocks the racks 31, 32, the racks being placed in the same relative position as the cam blocks. It will be apparent that as the stick S travels, the gear or pinion will mesh alternatively with the top and bottom racks, opposite rotational movement being given to the stick by the upper and lower racks.

From the above description it will be seen that there has been provided an apparatus for drying paper which will permit the paper to be supported at more than one line of support during its course of travel through the drying room or tunnel. As already indicated pole marks are formed when the paper is allowed to be supported on the pole without change of position. The present invention, inasmuch as it provides for a change of supporting position between the paper and the poles, results in the elimination, or the practical elimination, of the pole marks such as occur in ordinary drying apparatus.

What is claimed is:

1. In a paper drying device, the combination of a pair of relatively fixed sticks on which the paper is adapted to be alternatively supported, means for turning the sticks to present first one stick to the paper and then the other comprising a frame on

- which the sticks are supported for travel, longitudinally spaced abutments on the frame on either side of the line of travel of said sticks, and means affixed to one end 5 of said sticks adapted to coact with the abutments in succession, the coaction between the said means and abutments being such that the sticks are rotated first in one direction and then in the opposite direction.
- 10 2. In a paper drying device, the combination of a paper supporting member, a frame along which said member is adapted to travel, means for intermittently turning said member through one-half revolutions 15 in opposite directions during the travel of said member, said means comprising abutments arranged in staggered relation on either side of the line of travel of said member, and means on said member adapted to 20 engage the abutments in succession whereby the said member will be rotated in alternate directions as said member travels.
3. In a paper drying device, the combination with a plurality of paper supporting 25 members on which the paper is adapted to be hung in festoons, and a frame on which said members are supported for travel, of means for causing said members to revolve periodically through less than a complete revolution first in one direction and then in 30 the opposite direction whereby said members will contact with the paper at a plurality of points during the course of travel of said members, said means comprising a wheel 35 fixed on each of said members, and a plurality of spaced abutments arranged in staggered relation above and below the axis of each of said wheels, each of said wheels upon engaging said abutments being given a 40 partial revolution by one abutment and a reverse rotation by the next abutment.
4. In a paper drying device, the combination of a pair of sticks, a common shaft to which the sticks are affixed, an eccentric 45 on said shaft, a frame in which said block is slidable, a plurality of cam blocks supported on said frame on either side of the line of travel of the bearing block in longitudinally spaced relation, said cam adapted to pass between adjacent ends of said cam 50 blocks and to be rotated in passing therebetween.
5. In a paper drying device, the combination of a frame, a paper supporting member extending across said frame and adapted to be moved therealong, a plurality of blocks having inclined ends mounted on the frame on either side of the line of travel of said member and a cam affixed to said member, said cam disposed in the same vertical plane as said blocks, said cam adapted to be turned in passing between a pair of adjacent blocks.
6. The combination specified in claim 5, said paper supporting member constituting 65 a pair of round sticks extending in parallel relation and having a supporting shaft at either end, the cam being affixed to said shaft.
7. In a paper drying device, a pair of 70 sticks, means for holding the sticks in fixed parallel relation, a shaft extending from both ends of said sticks, a round wheel eccentrically affixed to said sticks and constituting a cam, bearings mounted loose on 75 said shaft at either end of the sticks, a frame across which the sticks are supported for travel by means of said bearings, a plurality of cam blocks affixed to the frame on either side of the line of travel of said 80 sticks, said cam blocks constituting elongated members having a flat surface and inclined ends, the adjacent ends of the said members being spaced longitudinally and vertically to form a gateway through which 85 the cam may pass, the cam in passing through the gateway being rotated one-half revolution and when entered through the gateway sliding between one of said cam blocks and the frame.
- In testimony whereof I affix my signature.

JOSEPH H. MILLER.
